[57] CLAIM

The ornamental design for a fluted golf putter shaft, as shown and described.

DESCRIPTION

FIG. 1 is a perspective view of my invention, showing my new design;

FIG. 2 is a perspective view thereof, the broken line showing of the grip and putter head are for illustrative purposes only and forms no part of the claimed design; and,

FIG. 3 is a perspective view of a second embodiment of the shaft as disclosed in FIG. 1, the broken line showing of the grip and putter head are for illustrative purposes only and forms no part of the claimed design.
